CLAIM

We claim the ornamental design for a surveillance camera, as shown and described.

DESCRIPTION

FIG. 1 is a perspective view of a surveillance camera of the present invention, with a lens being positioned towards the inside of the surveillance camera and shown in a closed position;

FIG. 2 is a bottom plan view thereof;

FIG. 3 is a side elevation view thereof;

FIG. 4 is a perspective view thereof, with the lens being rotated from the position shown in FIG. 1 and a partially open position; and,

FIG. 5 is a perspective view thereof, with the lens being positioned directly below and shown in an open position. The broken lines in the drawings are shown to illustrate the portions of a camera in which the design is embodied and form no part of the claimed design. Additionally, the dash-dot lines in the drawings define the boundary of the claim and form no part of the claimed design.

1 Claim, 5 Drawing Sheets
